UNITED STATES PATENT OFFICE

ANTONIO FIORE AND RICHARD A. ADE, OF PHILADELPHIA, PENNSYLVANIA

THREAD WAXING DEVICE

Application filed November 19, 1931. Serial No. 576,130.

Our invention relates to improvements in a thread waxing device and particularly relates to a device which may be used for waxing thread for shoe sewing machines.

5 The object of our invention is to provide a device adapted for use with liquid wax which does not require heating to maintain it in a liquid form.

A further object is to provide a waxing device comprising a liquid container with 10 means for rotatably mounting one or more spools of thread immersed in the liquid, whereby the thread may be drawn from the spool without displacing, or up-ending the 15 spool.

A further object is to provide a holder for the spool, or spools, which holder may be withdrawn from the liquid for the purpose of inserting new spools.

20 A further object is to provide means for supporting the holder upon the container, above the liquid level, in a position in which the liquid will drain into the container, during the insertion of new spools.

25 A further object is to provide a separate carrier for each spool. Said carrier being movable vertically upon the holder so that the spool of thread will always rest upon the bottom of the holder.

30 A further object is to provide means for locking and unlocking the spools upon the carrier, and provides means for operating the same without the necessity of handling of the parts which are covered with the liquid.

35 A further object is to provide an indicator upon the carrier for showing when the spools are "full" and "empty."

40 A further object is to provide a novel form of wiper upon the receptacle through which the thread is drawn for removing excess waxing liquid from the thread.

These together with various other details of construction and arrangement of the parts, which will be more fully described and claimed, constitute our invention.

Referring to the accompanying drawing Fig. 1 is a transverse vertical section, as on line 1—1, Fig. 2, showing the thread waxing device. Fig. 2 is a vertical longitudinal sectional view on line 2—2, Fig. 1. Fig. 3 is a

plan view of the device showing the lid in the open position. Fig. 4 is a perspective view of a thread waxing device for holding a single spool of thread.

In the drawing in which like reference characters refer to like parts, Figs. 1 to 3 illustrate a thread waxing device 5, constructed to accommodate two spools of thread. Said device comprises a container 6 having a front wall 7, a back wall 8, end walls 9 and 10 and a bottom wall 12, all secured together to form a container for a liquid waxing solution. A lid 14 is secured by hinges 15 to the back wall 8 and is detachably secured to the front wall 7 by a hook 16 or other suitable device 55 for holding the lid closed upon the container.

A holder 20 is provided for supporting one or more spool carriers, which carry the spools of thread. A full spool of thread 21 and an empty spool 22 are shown in Figs. 2 and 3. 70 The holder 20 fits loosely into the container 6 and provides means for holding the spools of thread immersed in the liquid, and for lifting the empty spools from the liquid, and for readily placing full spools upon the 75 holder.

The holder 20 consists of a back plate 24 and a bottom plate 25 rigidly connected with the back plate, and a brace plate 26 rigidly secured to the back and bottom plates. The 80 brace plate 26, at its upper portion, is provided with a finger hole 27 to facilitate in lifting the holder from the container.

85 Spool carriers 30 are mounted upon the holder 20, each consisting of a vertical rod 31 which is bent to a horizontal portion or shaft 32. The vertical rod is slidably mounted in a vertical guide 34 secured upon the back plate 24. The guide 34 is in the form of a split tube which embraces a portion of the rod 31 and a flat portion 35 which forms a supporting surface upon which the lower portion of the rod 31 slides.

90 A roller 38 is loosely mounted upon the horizontal shaft 32. Said roller is provided to receive the spool or tube 22 upon which the thread is wound. An enlarged washer or head 39 is rotatably mounted upon the front end of the shaft 32.

95 Front plates 40 are provided for guiding 100

the front ends of the shafts 32. Each plate 40 is secured by a hinge 41, to the front edge of the bottom plate 25 upon the holder. Said plate 40 is provided with a hole 42 of sufficient size to freely embrace the washer or head 39, and said plate 40 is also provided with a vertical slot 43 of sufficient width to embrace the shaft 32, and permit the shaft to move vertically in the slot and allowing the spool of thread to rest upon the bottom plate 25.

The vertical rod 31 is provided with a handle or pointer 45, on its upper end for lifting the carrier. When the carrier is lifted until the horizontal shaft 32 strikes the lower end of the tubular guide 34, the washer 39 is in alignment with the hole 42 in the front plate 40 and will freely pass through the hole 42. The front plate 40 may be swung to the horizontal position shown in Fig. 4, so that the empty spool or tube 22 may be removed from the roller 38 and a full spool of thread placed upon the roller. The front plate 40 is then raised until the washer passes through the circular hole 42. The front plate 40 will be retained in an upright position by the washer 39 when the horizontal shaft 32 occupies the vertical slot 43.

Stop plates 48 are secured upon the brace plate 26 and limit the inward movement of the front plates 40 toward the spools. The front plates 40 are provided for preventing any horizontal swinging movement of the shafts 32 during the unwinding of the thread from the spools, thus insuring the spools being maintained in their proper position.

The handle 45 forms a pointer which registers with markings upon the inner surface of the back wall 8 of the container, for indicating the amount of thread upon the spool. The level of the waxing liquid is maintained above the spools of thread and, as said liquid is opaque, the indicating devices for showing the quantity of thread upon the spools are of great advantage as it avoids the necessity of lifting the holder from the liquid for inspecting the spools.

When it is necessary to place a full spool of thread upon the carrier the holder 20 is lifted from the container, by means of the brace plate 26, to a position above the container.

The container is provided with a removable shelf 50, which is positioned immediately below the lid 14. The ends of the shelf are supported upon the opposite end walls 9 and 10 of the container. By removing the shelf 50 from the container the holder 20 may be lifted from the container and the shelf is again replaced upon the container and thus forms means for supporting the holder above the container in a position in which the liquid will drain into the container.

The shelf 50 is provided with depending

end flanges 51 which embrace the end walls 9 and 10 of the container. The end walls 9 and 10 are provided with recesses 52 to receive the shelf 50. The top edges 54 of the walls 9 and 10, within the recesses 52, are inclined downwardly toward the back wall 8 of the container, so that the shelf 50 and the holder 20 when supported upon the shelf, as shown in Fig. 4, will be inclined for draining the liquid toward the rear of the container.

The shoulders 55 formed at the ends of the recesses 52 form means for properly positioning the shelf upon the container, so that the shelf will not interfere with the closing of the lid.

A thread wiper 58 is provided for removing the excess waxing liquid from the thread as it is drawn from the spool. The wiper 58 is attached to the under side of the lid 14 by means of suitable fastening devices such as the bolts 59. The wiper consists of a layer of material 60 of relatively soft or open texture, such as felt, curled hair, or fiber, and a layer 61 of tenacious, or tough, material, 61, such as leather, or fabric, for retaining the felt, or fiber, in its proper form, and for tightly impinging upon the thread.

The layer of tough material 61 is provided with small holes 62 through which the thread passes. The felt or fiber and also the lid are also provided with holes which are in alignment with the holes 62 in the outer layer, through which the thread may be drawn for removing excess waxing material from the thread and evenly distributing the material upon the thread and insuring the individual strands of the thread being saturated with the waxing material. The wiper shown in Figs. 1 to 3 is provided with two holes 62 for the threads from the double spool holder. Thread guide plates 65 are secured upon opposite sides of the brace plate 26, for guiding the threads from the spools.

The shelf 50 is provided with a central opening 66 into which the thread wiper 58 loosely enters to permit the closing of the lid. Said shelf also has a slot 67 communicating with the central opening to permit the shelf to be inserted and removed from the container without interfering with the threads.

Fig. 4 illustrates a form of our invention constructed for holding one spool of thread. The container 70 is of rectangular form and the holder 71 is constructed with the brace plate 72 located at one side of the holder instead of in the center. The thread wiper 75 is provided with a single hole for the passage of the thread, otherwise the form shown in Fig. 4 is similar in construction to that shown in Figs. 1 to 3 and bear the same reference characters.

Various changes in the construction and

arrangement of the parts may be made without departing from our invention.

We claim:-

1. In a thread waxing device, a container for a waxing solution, spool holding means within the container, said container having a hole formed therein for the passage of a thread, a layer of tough material having a hole through the same for the passage of a thread, a layer of relatively soft fibrous material through which the thread passes, said layer of fibrous material interposed between the container and said layer of tough material, and means securing said layers upon the container. 70
2. In a thread waxing device, a container for a waxing solution, spool holding means within the container, a layer of tough material having a thread outlet hole formed through the same, yielding means interposed between the layer of tough material and the inner surface of the container, and said container having a thread outlet hole formed through the same in alignment with said hole in said layer. 75
3. In a thread waxing device, a container for a waxing solution, a bottom plate forming part of a holder removably mounted within the container, a vertical plate rigidly mounted upon said bottom plate, a brace plate secured to said bottom and vertical plates, and a spool carrier mounted upon said vertical plate. 80
4. In a thread waxing device, a container for a waxing solution, a bottom plate forming part of a holder removably mounted within the container, a vertical plate rigidly mounted upon said bottom plate, a brace plate secured to said bottom and vertical plates, a spool carrier upon said vertical plate, and means holding the spool carrier at right angles to the vertical plate. 85
5. In a thread waxing device, a container for a waxing solution, a bottom plate forming part of a holder removably mounted within the container, a vertical plate rigidly mounted upon said bottom plate, a brace plate secured to said bottom and vertical plates, a spool carrier and a guide upon said vertical plate in which the carrier is movable vertically. 90
6. In a thread waxing device, a container for a waxing solution, a bottom plate forming part of a holder removably mounted within the container, a vertical plate rigidly mounted upon said bottom plate, a brace plate secured to said bottom and vertical plates, a rod, a guide upon said vertical plate in which the rod is slidable vertically, a shaft having one end mounted upon the lower end of said rod forming a spool carrier, and guide means upon the holder in which the opposite end of the shaft is movable vertically. 95
7. In a thread waxing device, a container for a waxing solution, a bottom plate forming part of a holder removably mounted within the container, a vertical plate rigidly mounted upon said bottom plate, a brace plate secured to said bottom and vertical plates, a guide upon said vertical plate, a member slidable vertically in said guide, a shaft forming a spool carrier mounted upon the lower end of said member, and a pointer upon the upper end of said member for indicating the position of the shaft relatively to the bottom plate. 100
8. In a thread waxing device, a container for a waxing solution, a bottom plate forming part of a holder removably mounted within the container, a vertical plate rigidly mounted upon said bottom plate, a brace plate secured to said bottom and vertical plates, a front plate, a hinge mounting the front plate to the side of the bottom plate opposite to said vertical plate, a stop upon said brace plate against which the front plate takes when in the vertical position, a horizontally proportioned shaft forming a spool carrier, a guide upon said vertical plate in which one end of the shaft is movable vertically, a guide upon the front plate in which the front end of the shaft is movable vertically, and means for detachably securing the front end of the shaft upon the front plate for holding the latter against said stop. 105
9. In a thread waxing device, a container, a holder removably mounted within the container, a spool carrier movably mounted upon the holder, and an indicator upon said carrier for showing the relative position of the carrier to the holder. 110
10. In a thread waxing device, a container for a waxing solution, a bottom plate forming part of a holder removably mounted within the container, a vertical plate rigidly mounted upon said bottom plate, a brace plate secured to said bottom and vertical plates, a guide upon said vertical plate, a member slidable vertically in said guide, a shaft forming a spool carrier mounted upon the lower end of said member, and a pointer upon the upper end of said member for indicating the position of the shaft relatively to the bottom plate. 115
11. In a thread waxing device, a container, a bottom plate removably mounted within the container, a back plate positioned vertically and secured upon said bottom plate, a brace plate secured upon said bottom and back plates, said brace plate positioned centrally of the length of the bottom plate, front plates, hinges securing the front plates to 120
12. In a thread waxing device, a container, a bottom plate removably mounted within the container, a back plate positioned vertically and secured upon said bottom plate, a brace plate secured upon said bottom and back plates, said brace plate positioned centrally of the length of the bottom plate, front plates, hinges securing the front plates to 125
13. In a thread waxing device, a container, a bottom plate removably mounted within the container, a back plate positioned vertically and secured upon said bottom plate, a brace plate secured upon said bottom and back plates, said brace plate positioned centrally of the length of the bottom plate, front plates, hinges securing the front plates to 130

- the front edge of the bottom plate, stops upon the brace plate against which the front plates rest when in a vertical position, vertically positioned guides upon the back plate located at opposite sides of the brace plate, rods slidably mounted in said guides, horizontal shafts mounted upon the lower ends of said rods forming spool carriers, means for detachably securing the front ends of the shafts upon the front plates, and a thread wiper upon the container having thread outlet holes formed therein for the passage of threads from the spool carriers.
12. In a thread waxing device, a container comprising a horizontal bottom wall and vertical side walls, a spool holder removably mounted within the container, a plate forming a shelf, said plate having downwardly projecting end flanges arranged to embrace opposite side walls of the container, and said side walls having recesses formed therein to receive said plate and support the same above the holder when positioned within the container and for supporting the holder upon said plate when withdrawn from the container.
13. In a thread waxing device, a container comprising a horizontal bottom wall and vertical side walls, a lid hinged upon the upper portion of one of the side walls, a spool holder removably mounted within the container, a thread wiper secured upon the under side of the lid, said wiper having a thread outlet hole formed through the same, a plate forming a shelf removably supported upon the upper edges of the side walls of the container, and said plate having a recess formed therein to receive the thread wiper when the lid is closed.
14. In a thread waxing device, a container, a lid upon the container, a holder removably mounted within the container, spool carriers upon the holder, a thread wiper secured upon the under side of the lid, said wiper having thread outlet holes formed therein corresponding in number to the number of spool carriers, a plate forming a shelf removably supported upon the container upon which plate the holder may be supported when withdrawn from within the container, said plate having a recess formed therein positioned to be occupied by the thread wiper when the lid is closed, and said plate having a side opening formed therein communicating with said recess for the free passage of threads when the plate is being inserted or removed from the container.

In testimony whereof, we affix our signatures.

ANTONIO FIORE.
